UNITED STATES PATENT OFFICE.

WILLIAM EVENSEN, OF CHICAGO, ILLINOIS, ASSIGNOR TO THE GOSS PRINTING PRESS COMPANY, OF CHICAGO, ILLINOIS, A CORPORATION OF ILLINOIS.

PLATE-CLAMPING MECHANISM FOR PRINTING PRESSES.

Application filed November 28, 1923. Serial No. 677,427.

To all whom it may concern:

Be it known that I, WILLIAM EVENSEN, a citizen of the United States, and a resident of Chicago, in the county of Cook and 5 State of Illinois, have invented certain new and useful Improvements in Plate-Clamping Mechanism for Printing Presses, of which the following is a specification, reference being had to the accompanying drawings.

This invention relates to improvements in means for clamping in place stereotype plates upon a cylinder of a printing press, and it has for its leading object the providing of improved means for positively and simultaneously adjusting two alined clamps to bring them into operative or releasing position relatively to the stereotype plates on the cylinder, and which clamps by a 20 single operation of an adjusting means may be spaced at different distances apart to properly accommodate between them plates of different width. This object I accomplish by the means shown in the drawings and hereinafter described. That which I believe to be new will be pointed out in the claims.

In the drawings,—

Fig. 1 is a plan view of a portion of a 30 plate cylinder provided with my improvements, portions of the plates that are shown in connection with the cylinder being broken away;

Fig. 2 is an enlarged longitudinal section 35 taken at line 2—2 of Fig. 1;

Fig. 3 is a view similar to Fig. 2, but showing the clamping means moved out of plate-holding position;

Fig. 4 is a perspective view of the operating rod that passes loosely through the inner clamping member and by means of adjustable abutments that it carries controls the position of such clamping member;

Figs. 5 and 6 are enlarged cross-sectional views taken respectively on lines 5—5 and 45 6—6 of Fig. 2; and

Figs. 7 and 8 are, respectively, perspective views of the outer and inner movable clamping members.

Referring to the several figures of the drawings,—10 indicates an ordinary plate

cylinder mounted in the usual manner upon a shaft 11. At its transverse central portion the cylinder is provided with an annular abutment 12 against which the inner ends 55 of the plates at each side of that center abut as usual, such member 12 being beveled in the usual manner to correspond to the bevel on the edge of the plates. Two plates are shown on the cylinder at one side of such 60 central abutment, and the inner one, or that that lies against such abutment, is indicated by *a*, and the other or outer plate by *b*. 13 indicates slots in the surface of the cylinder and extending longitudinally thereof, in 65 which are slidably mounted a plurality of clamps as usual which project between the adjacent edges of the plates *a* and *b* for aiding in clamping such plates in place on the cylinder, as is understood. 15 indicates 70 other and similar longitudinally-extending slots in the surface of the cylinder and in alinement with the previously-mentioned slots, in which slots 15 are slidably mounted other clamps, indicated by 16, which are 75 adapted to engage with the outer edge of the outer plate *b*. Each two alined slots 13, 15, in the construction shown, are connected by a passage 17, as clearly shown in Figs. 2 and 3, and extending through each of such 80 passages and projecting into the slots 13 and 15 that are in alinement therewith is an operating rod 18. As the several operating rods 18 are alike and are each connected with like parts a description of one will of 85 course suffice. Intermediate of its ends the rod is, as clearly shown in Fig. 4, provided with a long slot 19 into which projects the end of a short screw-threaded plug 20 that is secured in the wall of the cylinder. Such 90 plug 20 will, of course, prevent any turning of the rod 18, but will permit its free longitudinal movement, as will be understood. At its inner end portion the rod 18 is screw-threaded for a considerable distance, such 95 screw-threaded portion passing through but not engaging with a bore 21 in the clamp block 14. The screw-threaded portion referred to is indicated by 22. At opposite sides of the clamp block 14 are nuts 23 and 100 24 that are screwed upon the part 22 of the rod, the nut 23 being adapted to be brought

in contact with the clamp 14 when such clamp is to be moved into plate locking position and the nut 24 being adapted to be moved into contact with such clamp in order that it shall be moved into position to allow of the removal or placing in position of the plates, as more fully described hereinafter. Against each of the nuts 23, 24 will preferably be screwed a set nut, as shown.

10 25 indicates a long screw lying in one of the slots 15 in the cylinder, said screw having threaded engagement with a screw-threaded bore 26 extending through one of the clamp blocks 16 that engages the outer edge of the outermost plate *b*. As clearly shown in Fig. 2, each of the screws 25 has its inner end portion hollow, as at 27, such hollowed portion being screw-threaded to receive and engage with the screw-threaded 20 end 28 of one of the rods 18. The exterior threads of the screw 25 are much coarser than the interior screw threads—preferably there being nine threads to the inch on the exterior and eighteen to the inch on the 25 interior, with the result, of course, that when the screw is turned the clamp 16 will be moved longitudinally of the cylinder twice as rapidly as will the clamp 14, as will be more fully described hereinafter.

30 29 indicates a semi-circular head at the end of the cylinder, the two semi-circular heads contacting at their diametric edges and each head being so mounted with relation to the cylinder that it may be moved away from 35 the end of the cylinder as shown in Fig. 3, or be moved up against such end as in Fig. 2, and connected with each of these heads are the series of screws 25 shown in the drawings, and it will be evident that a 40 drawing away from the cylinder of the head as in Fig. 3 will result in so drawing back the various movable clamps as to permit the plates *a* and *b* to be removed from the cylinder. As such heads 29 for this purpose are 45 old in the art I have not deemed it necessary to illustrate or describe the means by which they are attached and locked in place. It is also old to provide a coiled spring, such as shown at 30, for normally exerting 50 an inward pressure upon the screws that connect the heads with the clamps 16, such springs being provided to insure perfect contact between such clamps and the plate *b* notwithstanding any slight irregularities 55 in the edge of such plate.

In use the several screws 25 will be turned by a socket wrench or other tool to cause a proper spacing apart of the clamps 14 and 16 that each screw actuates, so that 60 after such adjustment has been made the several clamps will properly engage and hold the plates *a*, *b* whenever the heads 29 are moved up against the end of the cylinder as shown in Fig. 2. It will be understood that while continuing to use plates

of the same width there will be no need of making independent adjustments of the clamps 14 and 16 because the inward and outward movement of the heads 29 will always carry such clamps into proper operative and inoperative positions. When, however, plates of a different width from those theretofore used are to be used on the cylinder the screws 25 are to be separately rotated to effect new adjustments of the clamp blocks 14 and 16. If, for example, it be desired to use wider plates on the cylinder each screw 25 will be turned to draw back its clamp block 16 toward the end of the cylinder. Such turning of the screw will, 70 by reason of its internal threads being in engagement with the screw-threaded end portion 28 of the rod 18, also cause an endwise movement toward the end of the cylinder of that rod, but such movement of the rod will necessarily be less than the movement of the clamp block 16 owing to the difference in the number of threads to the inch between the exterior and interior of the screw 25. Such endwise movement of the rod 18 will not, however, affect the clamp block 14 until the nut 24 has been drawn into contact with it, but after such contact has been made the clamp block 14 will move 80 in unison with the clamp block 16, but, of course, at only one-half the speed of the clamp block 16 when the number of screw threads on the exterior of the screw 25 is half as many to the inch as the screw threads on the interior thereof. The clamp block 14 is to be moved sufficiently to provide something more than the necessary space between it and the fixed abutment 12 for the reception of a plate that is to be clamped 90 between those parts, such additional space over that required for the plate itself being for the purpose of enabling such plate to be readily inserted in place. So moving the clamp block 14 sufficiently to receive such a wider plate between it and the fixed abutment 12 will, of course, result in the clamp block 16 being moved quite considerably 100 farther than is really necessary to receive the wider plate that is to be held between it and the clamp block 14, but that is immaterial because after both of such wider plates have been placed on the cylinder the screws 25 will be reversely rotated so as to inwardly move the clamp blocks 16 and 14 that each controls. The clamp block 16 as it is thus moved inward will come into contact with the newly-placed wider plate *b* and force it inward toward and against the clamp block 14, which in turn will be moved 110 up into clamping relation to the newly-placed wider plate *a*, and by the time such position has been reached the more slowly moving nut 23 will have reached the clamp block 14. Thereafter the plates will remain 120 clamped in position, and when their removal 125 130

is desired there will be no necessity for rotating the screws 25, because the desired releasing of the clamps will be accomplished by drawing the heads 29 away from the end 5 of the cylinder, as before described. It will be evident, therefore, that when the clamp blocks have been adjusted by a turning of the screws 25 to plates of any width there is no occasion for the further turning of 10 those screws so long as plates of the same width continue to be used on the cylinder, inasmuch as the movements of the clamps into and out of operative position are always accomplished by a manipulation of 15 the heads 29, as described. As shown in Fig. 3 the nut 24 that constitutes the abutment that strikes against the clamp block 14 and moves such clamp block toward the end of the cylinder when the head 29 is 20 drawn away from the cylinder is so positioned on the rod 18 that it will move said clamp block far enough along in its groove 13 to permit the inner plate α to be readily removed and another one substituted 25 for it.

By my invention each set of aligned clamps will be always held spaced apart to approximately the required extent to receive between them a plate of any predetermined 30 width, and the clamp blocks 14 will be likewise held spaced from the fixed central abutment 12, and both of such clamping blocks will be caused to operatively engage the plates by a single inward movement of 35 the head 29. A further feature of advantage pertaining to the invention is that whenever it is desired to dispense with the outer plate, such as β , and print only from the inner plate, such inner plate can be 40 locked in place and released from locked position in just exactly the same manner as if the said outer plate were present on the cylinder, for it will be evident that the drawing back of the head 29 from the end 45 of the cylinder will, through the nut 24, cause the clamp block 14 to be drawn away from such plate as before described, whereas the moving of the head up against the end 50 of the cylinder will carry the nut 23 against said clamp block and thus move such clamp block tightly against said plate.

What I claim as my invention and desire to secure by Letters Patent, is—

1. The combination of a plate cylinder, 55 plate clamps carried thereby and movable longitudinally thereof, and means for adjusting said clamps to different relative positions simultaneously but at different speeds.

2. The combination of a plate cylinder, 60 two plate clamps carried thereby and movable longitudinally thereof, and rotatable means for adjusting said clamps to different relative positions simultaneously but at different speeds.

3. The combination of a plate cylinder, 70 two plate clamps in alinement with each other on said cylinder and movable longitudinally thereof, and rotatable means for adjusting said clamps to different relative positions simultaneously but at different speeds.

4. The combination of a plate cylinder, 75 two plate clamps carried thereby and movable longitudinally thereof, and rotatable adjusting means for first moving one of said clamps and thereafter moving both of said clamps in the same direction simultaneously but at different speeds to change the distance between them. 80

5. The combination of a plate cylinder, 85 two plate clamps carried thereby and movable longitudinally thereof, and adjusting means operatively connected with both of said clamps for successively moving them in the same direction.

6. The combination of a plate cylinder, 90 two plate clamps carried thereby and movable longitudinally thereof, and adjusting means operatively connected with both of said clamps for successively moving them in the same direction and thereafter continuing to move them simultaneously. 95

7. The combination of a plate cylinder, 100 two plate clamps carried thereby and movable longitudinally thereof, a screw device extending through a threaded opening in one of said clamps and adapted when turned to move such clamp, and other means connected with and actuated by said screw device for moving said second clamp in the same direction as the first clamp but over a shorter distance. 105

8. The combination of a plate cylinder, 110 plate clamps carried thereby and movable longitudinally thereof, of a screw device having two sets of threads that vary as to the number per inch, one set of said threads engaging with one of said clamps, and means actuated by the other set of threads for engaging with said other clamp, whereby said screw device when rotated will move both of said clamps simultaneously in the same direction but at different speeds. 115

9. The combination of a plate cylinder, 120 two plate clamps carried thereby and movable longitudinally thereof, an adjusting device carried by said cylinder, and means for operatively connecting said device with each of the clamps, the connecting means for one of the clamps operatively engaging it only after the other clamp has been moved.

10. The combination of a plate cylinder, 125 two plate clamps carried thereby and movable longitudinally thereof, a clamp-adjusting device carried by said cylinder and also extending longitudinally thereof, said device passing loosely through one of said clamps, and means on said device adapted to contact with said last-named clamp after 130

said clamp-adjusting device has made a partial operative movement.

11. The combination of a plate cylinder, plate clamps carried thereby and movable longitudinally thereof, of a hollow screw having exterior and interior threads, the threads on the interior being of a different number to the inch than those on the ex-

terior, the exterior threads being in engagement with one of said clamps, a screw-threaded non-rotatable rod in engagement with said interior threads, said rod passing loosely through said other clamp, and means on said rod for contacting with said last-named clamp. 10

WILLIAM EVENSEN.
